F. W. WARNER

TOY FIRE ENGINE HOUSE AND CALL BOX

Filed Oct. 8, 1925

Fred W. Warner.

ATTORNEY.

UNITED STATES PATENT OFFICE.

FRED W. WARNER, OF DENVER, COLORADO.

TOY FIRE-ENGINE HOUSE AND CALL BOX.

Application filed October 8, 1925. Serial No. 61,238.

This invention relates to toys and it has for its principal object to provide a miniature fire house, which, when its doors are opened from a distant point of operation, releases 5 a self-propelling toy fire engine, hose wagon or other appropriate vehicle.

A further object of the invention is to provide at the distant point of operation above referred to, a miniature call or alarm-box 10 such as are commonly used at street corners of towns and cities to apprise the fire or police department of a fire, and still another object resides in details of construction which permit of the manufacture of the toy at a minimum expenditure of labor and material.

With the above and other objects in view, my invention consists in the combinations and arrangement of parts illustrated in the accompanying drawings in the several views 20 of which like parts are similarly designated and in which—

Figure 1 represents a fragmentary and partially broken perspective view of the toy.

Figure 2, an enlarged fragmentary section 25 on the line 2—2, Figure 1,

Figure 3 a fragmentary elevation of one of the doors of the fire house, showing the form and arrangement of the spring by which it is opened,

Figure 4, a section on the line 4—4, Figure 2, showing an end of the slide bar which releases the catches by which the doors of the fire house are held in the closed position,

Figure 5, a section taken on the line 5—5, 30 Figure 2, showing the opposite end of the slide bar,

Figure 6, a face-view of the open alarm box,

Figure 7, a fragmentary section of the alarm box and the pedestal thereof taken in 40 the plane indicated by the line 7—7 in Figure 6.

Figure 8, an enlarged section on the line 8—8, Figure 2, showing the construction of the catches on the doors of the fire house, and 45 Figure 9, an elevation in outline of the fire house, showing a modification in the construction thereof.

Referring more in detail to the drawings, the toy comprises three separate elements, 50 namely, the fire house, designated by the numeral 5, the alarm box 6 and the self-propelling vehicle 7.

The first mentioned element is composed of a base 8 upon which is supported a house

9 which in its simplest form consists of four 55 walls and a roof. The rear wall of the house has an opening 10 for the insertion of the engine, and the thereto opposite front wall has a similar opening 12 which is normally closed by two doors 13.

The doors are hinged by pins 14 at their upper and lower edges, inserted in apertures of the base and the upper edge of the door-opening and they are provided with hinged catches 15 which, when the doors are closed, 60 engage a retaining lug 19 on a bar 20 which is slidably mounted on the base of the element.

The lug 19 is recessed to provide a ledge 19 which is embraced by the hook-shaped extremities of the two catches, and the bar on which the lug is formed is guided for longitudinal movement by screws 21 on the base extending loosely through slots in the bar. The ends of the bar are bent upwardly to provide 70 ledges, one of which is apertured for the insertion of a hook 22 on a pull-cord 23, and the other of which is engaged by the end of a light wire spring 24 which at its opposite extremity is fixed upon the base by means of a 75 wire staple 25.

The two doors of the fire house are opened by springs 26 which consists of simple lengths of thin spring-wire, the ends of which are bent and inserted in apertures in the inner 80 upright edges of the doors and the corresponding edges of the door-opening. The wires are inserted in the openings when the doors are in the open position so that when the doors are subsequently closed the wires are tensioned to spring back to their original condition and exert an impellant action upon the doors when the latter are released in the operation of the toy.

The alarm-box element of the invention 95 consists of a pedestal 27 upon which is supported a box 28 in simulation of the alarm-boxes used at street corners of towns and cities.

The pedestal is composed of a tubular stem 100 fixed on a weighted base in which is mounted a small pulley 29 for the guidance of the pull-cord 23. A second pulley 30 mounted in the box, supports the cord after it has been drawn through the tubular stem of the pedestal, and 105 a weighted handle 31 at the free end of the cord is suspended from the pulley in the box for ready manipulation.

A door 32 hinged on the box and provided with a catch 33 closes the opening of the box when not in use.

Either or both of the elements above described may be equipped with a gong that is sounded when the alarm-box is "pulled". A gong 34 mounted, for example, at a side of the fire house, has a clapper-mechanism that is actuated by a cord 35 connected with the pull-cord 23, and a gong 36 mounted at a side of the alarm-box has in connection with its operating mechanism an arm 37 extending in the path of a projection 38 on the spindle of the pulley 30 in the box.

15 The third element of the invention consists of a toy vehicle of the spring-operated type, preferably made in simulation of a fire-engine or hose-wagon.

A vehicle of this kind may be found in most 20 toy shops and it is, per se, not a part of the present invention.

The operation of the toy, the fire house and the alarm-box are placed apart at a distance determined by the length of the pull cord, the 25 doors of the fire house are closed by the catches which engage the retaining lug on the slide bar 20, and the vehicle 7 after its spring has been wound, is inserted in the fire house through the opening in the rear wall thereof 30 until its front wheels, designated by the reference character 39, rest against the doors as indicated in Figure 2.

A distinctive feature of the invention is that by lengthening the pull cord the alarm 35 box may be placed at a longer distance from the fire house, so that two children either in one or two rooms or at opposite ends of a hall or sidewalk, may take active parts in the operation, one of them, for instance, acting 40 as a policeman who upon the discovery of a fire "pulls" the alarm box and the other taking the part of the captain of the fire company who superintends the departure of the fire engine to the point of conflagration.

45 When the cord 23 is pulled in the alarm box by manipulation of the handle 31 the consequent lengthwise movement imparted to the bar 20 releases the catches from the retaining lug 19 with the result that the doors of the fire house are opened by the springs 26. Immediately upon the release of the doors, the vehicle which was restrained from action by the contact of its forward end with the doors, moves forwardly under the impellent influence of its previously wound spring, and upon leaving the fire house through the door-opening in the front wall thereof, it will continue its movement until its spring is unwound or until its progress is arrested by contact with a wall or piece of furniture.

It will thus be seen that the toy provides an amusing and entertaining diversion by imitating the actions incident to the giving of an alarm and the departure of a fire company upon the discovery of a fire, and the

imagination of the youthful players may be further stimulated by the sounding of the gongs at either the alarm box or the fire station or at both places if so desired.

It is an aim of the invention to construct 70 the elements included therein so that they may be produced at low cost. The springs, for example, acting upon the doors and the slide bar are of extreme simplicity and the alarm box and the fire house are so constructed 75 that they can be made of tin or other cheap material, the parts of which are fastened together by prongs as is common practice in the production of articles of this kind. The pedestal of the alarm box can be cast of lead or 80 other cheap composition and the base of the fire house may be made of wood or of bent metal if more desirable.

It is to be understood that changes in the form and construction of the elements comprised in the invention may be resorted to within the scope of the appended claims, it being intended, for example, in toys of 85 cheaper make to incline the floor of the fire house toward the door as shown at 40 in Figure 9 of the drawings and thereby cause the vehicle to move by gravity and without the use of a spring when the doors are opened.

Having thus described my invention, what I claim and desire to secure by Letters Patent is:

1. In a toy, the combination of a house element having a normally closed door, a self-propelling vehicle element having propelling means adapted to be pre-set, said element being held in check by the door when same is closed, and means for releasing the door at a point distant from the house element.

2. In a toy, the combination of a house element having a normally closed door, a self-propelling vehicle element having propelling means adapted to be pre-set, said element being held in check by the door when same is closed, and spring-controlled means outside of the house element for releasing the door.

3. In a toy, the combination of a house element having a normally closed spring-actuated door, a self-propelling vehicle element having propelling means adapted to be pre-set, said element being held in check by the door when same is closed, and means outside of the house element for releasing the door.

4. In a toy, the combination of a house element having a normally closed door, a self-propelling vehicle element having propelling means adapted to be pre-set, said element being held in check by the door when same is closed, a call box element adapted to be placed at a distance from the house element, and means for releasing the door of the house element at the call box element.

5. In a toy, the combination of a house element having a normally closed door, a self-propelling vehicle element having propelling means adapted to be pre-set, said element be-

ing held in check by the door when same is closed, means outside of the house element for releasing the door, an alarm, and an appliance for sounding the alarm by action of the releasing means.

6. In a toy, the combination of a house element having a door, a catch appliance adapted to hold the door in a closed position, a self-propelling vehicle element having propelling

10 means adapted to be pre-set, said element being held in check by the door when same is closed, and a pull cord outside of the house element connected with the appliance to release the door.

15 7. In a toy, the combination of a house element having a door, a catch appliance adapted to hold the door in a closed position, a self-propelling vehicle element having propelling means adapted to be pre-set, said element being held in check by the door when same is closed, a pull cord connected with the appliance to release the door at a point remote from the house element, and a call box element having

20 means for the movable support of the pull 25 cord.

8. In a toy, the combination of a house element having a door, a catch appliance adapted to hold the door in a closed position, a self-propelling vehicle element having propelling

30 means adapted to be pre-set, said element being held in check by the door when same is closed, a pull cord for the adjustment of the appliance to release the door at a point remote from the house element and a call box element

35 comprising a hollow pedestal, a box thereon, and means for the movable support of the pull cord passing through the pedestal into the box.

9. In a toy, the combination of a house element including hinged doors, pivoted catches 40 on the doors, a slide bar having a retaining

lug for engagement with the catches, a single piece of spring wire fastened at one end on the house element engaging the bar at its opposite end and urging the lug into engagement with the catches, a pull cord on the slide bar to release the doors at a point remote from the house element, and a vehicle element restrained by the doors when same are closed, means to propel the vehicle when the doors 50 are opened.

10. In a toy, a house element having a hinged door, a spring to open the door, composed of a single piece of wire fastened at its ends at an edge of the door and a corresponding edge of the door-opening, and torsioned when the door is closed, a vehicle element adapted to be automatically propelled when the door is opened, a catch appliance to hold the door in its closed position, and means connected with the appliance to release the door at a point remote from the house element.

11. In a toy, the combination of a house element having a normally closed door, a self-propelling vehicle element having propelling 65 means adapted to be pre-set, said element being held in check by the door when same is closed, a call box element adapted to be placed at a distance from the house element, an alarm on the call box, and means at the call box for 70 releasing the door and sounding the alarm.

12. The combination with a support and a door hinged thereon, of a single piece of spring wire extending lengthwise with relation to the pivotal axis of the door and fastened at its ends to the door and to the support, the wire being applied to the door in an open position to be torsioned by the pivoted movement of the door to a closed position.

In testimony whereof I have affixed my signature.

FRED W. WARNER.
